FIG. 5

FIGURE 1 is a perspective view taken from the top and left front side of a side delivery rake embodying my new design;

FIGURE 2 is a perspective view taken from the top and right rear side of the rake shown in FIG. 1;

FIGURE 3 is a perspective view taken from the top and rear side of the rake shown in FIGS. 1 and 2;

FIGURE 4 is a top plan view of the rake shown in FIGS. 1, 2, and 3; and

FIGURE 5 is a right side view of the rake.

The dominant features of the design reside in the portions shown in full lines.

I claim:

The ornamental design for a side delivery rake, substantially as shown and described.
